INVENTOR.
Frederic G. Hulme,
BY
Lewis S. Blackmon ATTORNEY.

UNITED STATES PATENT OFFICE.

FREDERIC G. HULME, OF TACONY, PHILADELPHIA, PENNSYLVANIA.

LOOM.

Application filed August 1, 1925. Serial No. 47,533.

To all whom it may concern:

Be it known that I, FREDERIC G. HULME, a citizen of the United States of America, residing at Tacony, Philadelphia, in the State of Pennsylvania, have invented certain new and useful Improvements in Looms, of which the following is a specification.

This invention relates to improvements in looms for weaving curved fabrics, and particularly to looms of that type, such as ribbon looms, for weaving narrow ware and employing conical tension or take-up rolls or the equivalent for governing the feed of the warp threads to give a curved form or curvilinear set to the woven fabric. More particularly the invention relates to a loom for weaving a novel and improved spiral strip fabric of a kind specially adapted to be formed into flat circular rings of the type used as facings or liners for automobile friction clutches and the like. A fabric of this character such as produced by the loom construction in accordance with the present invention, and as hereinafter fully described, constitutes the subject-matter of my copending application executed of even date herewith, filed Aug. 1, 1925, Serial No. 47,532.

As ordinarily made, a facing or liner of this character is cut out in annular form from a straight woven fabric, the ends of the annulus being brought to abut and joined by means of metallic staples, the flat facing ring thus formed being saturated or impregnated with a lubricating and water-proofing composition. An objection to this method of manufacture is that both edges of the ring are cut edges which are more or less quickly frayed by wear to a sufficient extent to impair the efficiency of the clutch. Another objection to this method of manufacture is the waste of material and general lack of strength, due to the fact that the warps are short and disposed at oblique angles to the ring edges instead of extending parallel with the edges of the ring and from end to end thereof, and the picks instead of extending radially to the axis of the ring, are also disposed at oblique angles to the ring edges, the structure thus being too weak to withstand for any considerable period of time without disintegration the tensile stresses to which it is subjected by the action of the clutch.

Attempts have been made to overcome these objections by cutting the annulus from which the ring is to be formed out of specially woven curved fabric, which must be stretched more or less into shape after the cutting action, with the result of securing a somewhat better disposition of the warp and weft threads to secure greater strength, but without overcoming the other objections mentioned. Attempts have also been made to overcome the noted objections by weaving the cloth in a curved strip of the desired width, with inner and outer selvaged edges, in which the curved formation is obtained by passing the material as formed between conical take-up rollers operating to give the curved outline to the fabric. All prior weaving methods of this kind, however, with which I am familiar have been defective and fall short of the desired result, for the reason that the arrangement of the conical take-up roll with respect to the weaving mechanism, as well as the construction of the latter in all prior looms with which I am familiar and which have been used for the purpose, has been such that a uniform tension of the warp and pick threads could not be obtained, the threads being bunched and woven very compact and under high tension at the inner edge of the strip and looser and of progressively less tension toward the outer edge of the strip, resulting in the production of an imperfectly curved strip which must be mechanically shaped into finally curved form after weaving and which is furthermore objectionable in that the strip is thicker and of maximum strength in the region of its inner edge and relatively thinner and of materially less strength in the region of its outer edge. The weave of this strip is also such that the picks extend more or less irregularly at oblique angles to the axis of a ring facing formed therefrom, thus reducing its strength in a transverse direction. A strip of this kind as woven, therefore, is not of uniform tension, and hence not of uniform strength, is not flat or of even thickness throughout, and must be mechanically finished before being rendered serviceable for use. In mechanically finishing such a strip it is saturated with the lubricating and waterproofing compound and then cut or planed down until it is of uni-

form thickness and its surfaces are flat and smooth. The objection to this operation is that the resultant product is materially weakened by the cutting and fraying of its threads in order to reduce it to a flat condition, reliance being placed upon the compound with which it is saturated to keep the threads intact, as a result of which rings of this character have inherent weaknesses and lack durability and efficiency. When such a facing is in use, the wear of the surfaces causes loosening of the frayed yarns and slipping of the obliquely disposed picks, producing lumpy formations particularly in the region of the outer edge of the facing and binding or sticking of the clutch elements making the clutch jerky and irregular in action.

One object of my present invention is to provide a loom for producing a spirally curved fabric strip which is so woven as to be uniformly flat from edge to edge and of uniform tensile strength throughout, which strip is capable of use for the production of a smooth-surfaced facing ring or liner without subsequent treatment of any kind which will impair its strength and efficiency, and which by reason of its uniform tensile strength will be of maximum durability.

Another object of the invention is to provide a loom for producing a woven fabric strip in which the picks or weft threads will be arranged in the completed ring at all points radially to the axis of the ring, ensuring the firm retention of all the ring threads in proper relationship and a smooth working action of the ring and the avoidance of any tendency to displacement of the ring threads liable to impair the strength or efficiency of the ring.

Still another object of the invention is to provide a loom for producing a spiral fabric which may be sold by the textile manufacturer to the automobile manufacturer or dealer as a stock strip of any given length or width, from which sections may be cut as required for the making of clutch rings of a standard width and any standard diameter, and which operation of completing a ring may be performed, without stretching or other mechanical shaping, by simply bringing the ends of the cut out section in abutting relation and stapling or otherwise joining them together.

Still another object of the invention is to provide a loom having a novel construction and cooperative working arrangement of weaving and take-up mechanisms whereby a curved fabric designed for the purpose described and for such other purposes as it may be adapted may be rapidly and economically made.

The invention consists of the features of construction, combination and arrangement of parts, hereinafter fully described and

claimed, reference being had to the accompanying drawing, in which:

Figure 1 is a view, partly in elevation and partly in section, of a portion of a loom embodying my invention, looking from the front toward the weaving and take-up mechanisms.

Figure 2 is a vertical section on line 2-2 of Figure 1.

Figure 3 is a top plan view of one of the shutters.

Figure 4 is a view of a length of spiral fabric produced by the loom.

Figure 5 is a plan view of a clutch facing or liner formed from the improved fabric.

Figure 6 is a diagrammatic view showing the weave of the fabric.

Figure 7 is a transverse section on line 7-7 of Figure 5.

Referring now more particularly to the drawings, in which I have shown only so much of the loom mechanism as is necessary for a complete disclosure of my invention, 1 designates the vibratory batten or lay of the loom operated by suitable means, such as the crank mechanism 2, from a suitable part of the loom driving mechanism, and 3 is the reed carried by and movable with the batten and detachably and adjustably mounted thereon for regulating the width and curve of the woven fabric, as hereinafter fully described.

The batten includes a beam 4 formed in its underside with a grooved guideway 5 for a reciprocating shuttle-actuating rack bar 6, suitably operated at proper time periods from the loom mechanism. The batten also carries shuttle blocks 7 provided with grooved guideways 8 for the shuttles 9, which blocks 7 are properly disposed to form the weaving-in spaces or passages 10 between adjacent blocks 7 across which the shuttles move back and forth, as in multiple ribbon looms, for carrying the filler or weft threads back and forth through the shed. In accordance with my invention the use of a breast beam and the usual guides for the fabric as woven is dispensed with, and the usual order of arrangement of the rack bar 6 and its gearing connection with the shuttles is reversed, that is to say, the rack bar is disposed above instead of below the plane of the shuttles and extends across the top instead of the bottom of the passages 10, and accordingly the teeth of this rack bar are formed upon its bottom edge and mesh with pinions 11 journaled on the shuttle blocks 7, which pinions engage rack teeth 12 formed upon the upper surfaces instead of the bottom surfaces of the shuttles, whereby said shuttles are actuated. This arrangement leaves the base of each passage 10 clear for the positioning therein of a take-up roll 13 and the arrangement for cooperation therewith of a press roll or tension roll 14, com-

pleting with the parts of the weaving mechanism above described a novel organization for a novel weaving action in the production of a curved fabric.

5 As shown, the take-up roll 13 is of conical form and is mounted for rotation upon an axis 15 inclined to the horizontal, and this roll is so placed that the upper surface of its periphery 16 is disposed in a horizontal plane, parallel with the plane of travel of the shuttles, and extends longitudinally across the bottom of the passage 10. The position of the surface 16 is also such that its vertical center, in the line of its axis 15, 10 is located immediately below and coincident with the vertical plane of the weaving-in point, beating-in point or fell point of the fabric. The roll 14 is of a conical form conforming to that of the roll 13 and is mounted for rotation upon an axis 17 parallel with the axis 15 and so as to bear upon the inner face of the roll 13 below the plane of the shed space. In practice the roll 14 is also 15 suitably mounted for movement toward and from the roll 13 and, by means of springs or weights, is made to bear with yielding pressure against the roll 13. Roll 13 is provided with a gear 18 meshing with a gear 19 on the driven take-up shaft 20, whereby 20 said roll 13 is positively driven for a take-up action, the roll 14 being driven by frictional engagement with the roll 13 and an intervening portion of the formed fabric clamped between the surfaces thereof or by positive 25 gearing 19', such as shown. From the beating-in or fell point against the upper surface of the periphery 16 of roll 13 the completed cloth material 21 woven by the loom mechanism from the warp threads 22 and 30 weft threads 23 passes in the form of a bight around the outside and underside of the roll 13, thence upwardly between and is gripped by the opposed faces of the rolls 13 and 14 and thence over the top of the roll and down 35 upon the inner side thereof. The cloth is thus woven directly against the upper surface of the roll 13 and trained about and gripped by the rolls in such manner as to secure a positive take-up motion without 40 slipping and so that the cloth will be held with a desired tension at the weaving moment to secure the desired shaping and uniform tension weaving action as hereinafter described.

45 The warp threads 22, 23 are drawn out and permitted to feed up under the action of the take-up roll in varying lengths or rates in proportion to the circumference of the tapered roll 13 at a point where a given warp 50 thread passes over the roll in the fabric. Hence in the weaving and take-up actions the formed cloth will be given a curved contour or curvilinear set proportionate to the taper contour of the roll, the resultant fabric being in the shape of a continuous nar-

row flat strip woven on spiral lines. For the purpose of enabling the width and curvature of this strip to be varied within given limits, the reed 3 is made detachable and also adjustable across the passage 10 and 55 longitudinally of the upper face of the roll 13. To this end the reed is mounted at its upper end in a guideway 24 formed in the batten and lies between one wall of said guideway and a clamping strip 25, the ends 60 of which extend at opposite sides beyond the limits of adjustment of the reed and are engaged by clamping bolts 26 and a clamping sleeve 26', whereby the clamp may be released to permit of a desired adjustment of 65 the reed along the roll to vary the diameter curve of the cloth, and then tightened to hold the reeds firmly in adjusted position. By the use of reed of different widths cloth 70 of varying widths may be woven.

75 In operation, the take-up roll takes up the fabric as formed and draws the warp threads forward and then stops, the shuttles operate to lay the filler or weft threads forward and backward through the shed, 80 and at the proper time periods the batten and reed operate to perform the beating-in action. As the cloth is formed and drawn under tension around the take-up roll it is 85 given its curvilinear set. An important feature of my invention resides in the fact that, 90 by means of the construction described, the batten and reed weave the threads directly against the face 16 of the roll 13 the highest point of which lies in a vertical plane which 95 coincides with the weaving-in point or fell point of the fabric. As this is done directly against the upper face of the roll 13 while the preceding woven portion of the fabric 100 is held fast about the roller 13 and between the rollers 13 and 14, the subsequent drawing 105 out of the fabric about the take-up roll, each time a weaving-in action is performed, will result in an accurate shaping of the fabric 110 in the exact curvilinear form desired against a shaping surface while the fabric drawn about that surface is stretched and held under high tension, and so that a closely woven cloth woven under uniform tension from 115 edge to edge of the fabric will be produced. This follows further from the fact that as the portion of the cloth between the fell point and the point at which the cloth is clamped between rolls 13-14 is very short, 120 no material relaxation in the tension of the warp threads due to the impact of the batten and reed at the weaving moment can occur, such as to cause variations of tension between the warp threads of different length, and hence the fabric will be woven 125 with a substantially uniform high tension from edge to edge thereof. Therefore there will be an entire avoidance of close weaving under very high tension causing bunching of 130 the threads at the short radius curve line of

the fabric and progressively looser and lower tension weaving between the same and the long radius curve line of the fabric, with a variation in density and thickness of the 5 fabric, such as occurs in the weaving of narrow curved fabrics on all prior constructions of looms with which I am familiar. While with my construction of loom the threads may be, and preferably are, woven 10 at fairly high tension, an abnormal tension is not necessary in order to produce a cloth of great strength, since the weave is such as to produce a cloth in which the arrangement of the threads is such as to secure great 15 strength and durability without the necessity of making the tension abnormally high.

Figure 4 shows a length of a narrow curved fabric 26 produced by the loom. This fabric is spirally curved, on a determined line of curvature, conforming to the 20 portion of the take-up roll from which it is drawn and the position of the reed relative thereto. The diameter curve of the fabric produced, for the production of a facing 25 of any given diameter, may be varied by varying the position of the reed to cooperate with portions of different diameters of the take-up roll, as previously described and as will be readily understood. By the use of 30 reeds of different widths, and proper adjustment of a reed of any given width with respect to the roll, a fabric of any given width and any given radius of curvature may be produced for the production of facing rings 35 of different widths and diameters. A strip 26 of a given width and curvature may be cut up as a stock strip from which flat facing rings 27 of the kind shown in Figure 5 may be made. This facing may be produced 40 from the strip section by simply bringing the ends of the strip section in abutting relation and uniting them by metallic staples 28 or other suitable fastening means. This may be done without in any other manner previously shaping the fabric. A ring thus 45 made when saturated with a lubricating and waterproofing substance or compound is ready for use. The fabric of which this ring is made, as shown particularly in Figures 5, 6 and 7, is provided with selvaged 50 inner and outer edges 29 and 30 and is formed of warp threads 22 extending from end to end of the fabric section and along and parallel with the selvaged edges thereof 55 and concentric with the axis of the ring facing, and of weft threads or picks 23 which extend at right angles to the warp threads engaged thereby across the fabric and at all points radially to the axis of the ring facing. The threads of the ring facing are 60 thus so arranged as to give great strength to the fabric and mutually reinforce each other to withstand the circumferential and radial stresses and strains to which the facing 65 is subjected in service operations. The

fabric thus produced, and the resulting ring facing, further are of equal thickness and density across the fabric between the selvaged edges, and of uniform or substantially uniform tension throughout, being devoid of any bunching of the threads or material variations in thickness at any point, so that the ring facing may be used with the fabric in pristine condition and without the necessity of any trimming operations causing cutting, abrasion or other weakening of the threads. A clutch facing made from this material, therefore, possesses maximum strength and durability and capacity for wear. In practice the take-up roll may be of such a degree of taper and diameter at any given point that the fabric strip produced will consist of a succession of convolutions of a given curvilinear length and set and capable of being separated along transverse lines, as along lines *a*—*a* in Figure 4, for the formation of individual ring facings therefrom, each section being suitable for directly making a ring facing by simply bringing its ends together and stapling or otherwise uniting such ends, as previously described. Inasmuch as ring facings of different widths and diameters may be made from sections of such a fabric made of different widths and spiral curvatures, it will be evident that the material may be sold to automobile manufacturers, dealers, repairmen and others as stock material from which clutch facings or liners may be readily and conveniently made for use.

In the example illustrated I have shown a single ply fabric of plain weave, but it will, of course, be understood that I do not limit myself to any particular weave or to any particular number of plies of the fabric, as many forms of weaves may be used and the fabric made of single ply or two or more plies, as desired.

Having thus fully described my invention, I claim:—

1. In a loom, a tapered take-up roll, and weaving mechanism operating to form the weave directly against a portion of the periphery of said roll.
2. In a loom, a tapered take-up roll, a presser roll operative to hold a bight of the woven material about a portion of the periphery of said take-up roll, and weaving mechanism operating to form the weave directly against another portion of the periphery of said take-up roll.
3. In a loom, a tapered take-up roll supported on an axis inclined to the horizontal and having the upper portion of its periphery disposed in a horizontal plane, and weaving mechanism operating to form the weave directly against the upper horizontal portion of the periphery of said roll.
4. In a loom, a tapered take-up roll, and weaving mechanism including a batten and

- a reed operating to form the weave at a point directly against a portion of the periphery of the roll, the roll and reed being relatively adjustable in a direction longitudinally of said roll.
5. In a loom, a tapered take-up roll, a presser-roll operating to hold a bight of the woven material about a portion of the periphery of the take-up roll, and weaving mechanism including a batten and a reed operating to form the weave directly against another portion of the periphery of the take-up roll.
6. In a loom, a tapered take-up roll supported on an axis inclined to the horizontal and having the upper portion of its periphery disposed in a horizontal plane, and weaving mechanism operating to form the weave directly against the periphery of the roll at the highest point of the horizontal portion of the periphery of the roll.
7. In a loom, a tapered take-up roll, a presser-roll operating to hold a bight of the woven material about a portion of the periphery of the take-up roll, and weaving mechanism including a batten and a reed operating to form the weave directly against another portion of the periphery of the take-up roll, the roll and reed being relatively adjustable in a direction longitudinally of said roll.
8. In a loom, a tapered take-up roll, and weaving mechanism including a batten and a reed operating to form the weave above and in vertical alinement with the axis of the roll and directly against the periphery of the roll, the reed being adjustable on the batten in a direction lengthwise of the periphery of the roll.
- 40 9. In a loom, a tapered take-up roll supported so as to dispose a portion of its periphery in a horizontal plane parallel with and on one side of the weft feed line, and weaving mechanism including a batten and reed having a working motion on a line at right angles to and in a plane above the horizontal plane of the roll and operating to form the weave directly against the upper surface of the periphery of said roll.
- 45 10. In a loom, weaving mechanism including a batten and a reed, and a tapered take-up roll supported on an axis inclined to the horizontal and having the upper portion of its periphery disposed in a horizontal plane longitudinally at right angles to and below the plane of weaving-in motion of the batten and reed, said batten and reed operating their beating-in motion to form the weave above the roll and in the vertical plane of its axis and directly against the horizontally disposed upper surface of the periphery of the roll.
- 50 11. In a loom, weaving mechanism including a batten and a reed, a tapered take-up roll supported on an axis inclined to the horizontal and having the upper portion of its periphery disposed in a horizontal plane longitudinally at right angles to and below the plane of weaving-in motion of the batten and reed, said batten and reed operating on their beating-in motion to form the fell directly against the horizontally disposed upper portion of the periphery of the roll in a vertical plane coincident with its axis, and a conical yieldingly mounted presser-roll disposed upon the relatively inner side of the take-up roll and operative to hold a portion of the completed fabric against said side of the take-up roll.
- 55 12. In a loom, a batten having a passage for the throw of the weft threads, a shuttle movable across said passage and provided with rack teeth, a rack bar disposed above said passage, pinions meshing with the teeth of the rack bar and shuttle, a reed carried by the batten and depending into said passage, a tapered take up roll supported so as to be disposed at the base of said passage at the weaving moment, said batten and reed operating on their weaving motion to form the weave at a point in immediate proximity to the surface of said roll.
- 60 13. In a loom, a batten having a passage for the throw of the weft threads, a shuttle movable across said passage and provided with rack teeth, a rack bar disposed above said passage, pinions meshing with the teeth of the rack bar and shuttle, a reed carried by the batten and depending into said passage, a tapered-take-up roll supported on an inclined axis and having the upper portion of its periphery arranged in a horizontal plane, said roll being arranged so as to be disposed at the base of said passage at the weaving moment, said batten and reed operating on their weaving motion to form the weave at a point in immediate proximity to the surface of said roll.
- 65 14. In a loom, a batten having a passage for the throw of the weft threads, a shuttle movable across said passage and provided with rack teeth, a rack bar disposed above said passage, pinions meshing with the teeth of the rack bar and shuttle, a reed carried by the batten and depending into said passage, a tapered take up roll supported so as to be arranged at the base of said passage at the weaving moment, and a tapered yieldingly mounted presser-roll arranged upon the relatively inner side of the take-up roll, said batten and reed operating on their weaving motion to form the weave at a point in immediate proximity to the surface of said roll.
- 70 15. In a loom, weaving means, and a take-up device having a draw surface formed to impart a curvilinear set to the fabric, the weaving means being operative to form the weave in direct contact with a portion of said draw surface of the take-up device.

16. In a loom, a batten having a passage for the throw of the weft threads, a shuttle movable across said passage, a reed carried by the batten and depending into said passage, a tapered take up roll supported so as to have the upper portion of its periphery disposed so as to lie in a horizontal plane at the base of said passage at the weaving moment, and shuttle drive gearing arranged 10 on a line between the upper surface of the shuttle and base of the batten.
17. In a loom, a batten having a passage for the throw of the weft threads, a shuttle movable across said passage, a reed carried 15 by the batten and depending therefrom into said passage, a tapered take up roll supported for rotation with the upper portion of its periphery arranged so as to be horizontally disposed at the base of said passage at the weaving moment, gearing for 20 operating the shuttle, and means for adjusting the reed transversely of said passage in the direction of length of the take up roll.
18. In a loom, a batten having a passage 25 for the throw of the weft threads, a shuttle movable across said passage and provided with rack teeth, a rack bar disposed above said passage, pinions meshing with the teeth of the rack bar and shuttle, a reed carried 30 by the batten and depending therefrom into said passage, a tapered take up roll supported for rotation upon an inclined axis so that the upper surface of its periphery will be horizontally disposed at the base of 35 said passage at the weaving moment, and means for adjusting the reed transversely of the passage and in a direction longitudinally of the take up roll.

In testimony whereof I affix my signature.

FREDERIC G. HULME.
